Patented July 27, 1920.

FIG. 1

FIG. 2

FIG. 3

INVENTOR

B. E. BEADLE

By *Joseph J. O'Brien*

ATTORNEY

UNITED STATES PATENT OFFICE.

BLANCHE E. BEADLE, OF SPRINGFIELD, MASSACHUSETTS.

HAIR-SUPPORT.

1,347,987.

Specification of Letters Patent. Patented July 27, 1920.

Application filed April 8, 1919. Serial No. 288,615.

To all whom it may concern:

Be it known that I, BLANCHE E. BEADLE, a citizen of the United States of America, and resident of Springfield, in the county of 5 Hampden and State of Mass., have invented certain new and useful Improvements in Hair-Supports, of which the following is a full, clear, and exact description.

This invention relates to improvements in 10 hair forms or supports and one of its leading objects is to provide a hair form, wherein the frame consists of companion jaws connected to each other so that hair may be clasped between the jaws, and shaped thereon to present an attractive appearance.

Another object of the invention is the provision of a hair form, consisting of a frame formed of a single piece of wire, and shaped to provide companion arched jaws, and interlacing portions, whereby the jaws may be 20 locked to each other, to clasp the hair between the jaws.

With the above and other objects in view the invention consists in certain new and 25 useful constructions, combinations, and arrangements of parts, clearly described in the following specification and fully illustrated in the accompanying drawings, in which:—

Figure 1 is a plan view of my improved 30 hair form, shown closed.

Fig. 2 is a plan view thereof, shown open.

Fig. 3 is a side elevation thereof, shown closed.

Referring to the accompanying drawings 35 illustrating the practical embodiment of my invention 5 and 6 designates the companion jaws of the improved form.

The jaws 5 and 6 are formed from a single 40 piece of wire, though, of course a number of pieces of wire may be employed. Each jaw consists of an outer curved portion, and an inner clasping portion. The jaw 5 consists of the curved marginal frame bar 7, which is continuous with the outer marginal frame bar 8 of the jaw 6. A bar 9 is extended from the mouth 10 to the opposite side of the frame, and this bar is formed with an outwardly offset portion 11, preferably located near the mouth 10, and which offset portion 45 11 is adapted to interlace with the outwardly offset portion 12 of the bar 13, which forms part of the jaw 6. The bar 9 is provided with a spring tensioning bend 9^a, while the bar 13 is provided with a similar bend 13^a,

which are offset outwardly from each other 55 to provide a hair space 14 therebetween, as shown in Fig. 1, whereby a considerable quantity of hair may be grasped. The bars 9 and 13 are connected by the twisted terminals 15 to the frame, at a point opposite the 60 mouth 10.

In its open position, as shown in Fig. 2 the jaws will be held by spring tension away from each other, so as to provide a wide clearance for the admission of hair between 65 the opposing bars of the jaws. By forcing the jaws toward each other and pushing the offset portion 12 of the bar 13 under the offset portion 11, of the bar 9, the jaws will be 70 locked to each other, so that the hair will be 75 grasped between the jaws, and the form retained in its selected position on the head.

The bars 9 and 13 are arched, as shown in Fig. 3, so that hair positioned or wound thereon will be elevated above the head on 75 which the form is disposed.

Having described my invention I claim:—

1. A hair form consisting of a frame formed wholly of companion hair clasping jaws flexibly connected to each other to open 80 the width of the frame.

2. A hair form consisting of a frame formed wholly of companion hair clasping jaws flexibly connected to each other to open 85 the width of the frame, each jaw having a bar offset to interlock with the other jaw, whereby the jaws will be held closed about the hair.

3. A hair form consisting of a frame formed of a C-shaped marginal bar and opposing bars extending from points on one side of the frame to points on the opposite side of the frame and connected thereto, said opposing bars being spaced from each other at certain points to provide a hair receiving 90 space, and offset at certain other points to interlock with each other, to clasp hair therebetween.

4. A hair form consisting of companion hair gripping jaws, each jaw having a curved marginal bar and a bar connecting opposite points on said curved marginal bar, the jaws being connected to each other, and the connecting bars being offset to interlock 95 with each other.

5. A hair form consisting of D-shaped jaws substantially equal in width and connected to each other so as to provide oppos-

ing hair gripping jaws the width of the form.

6. A hair form consisting of a frame having a curved marginal bar and opposing

5 hair gripping bars, the marginal bar and the hair gripping bars being united to each other to provide a mouth and a hair receiv-

ing space substantially equal to the width of the frame, the jaws being formed so that they may be coupled to each other to have 10 anchoring connection with the hair.

Signed by me at Springfield, Mass.

BLANCHE E. BEADLE.
